United States Patent Office

Des. 213,841

Patented Apr. 15, 1969

213,841

BOWL OR SIMILAR ARTICLE

Frank J. Benes, Lancaster, Ohio, assignor to Anchor
Hocking Glass Corporation, Lancaster, Ohio, a
corporation of Delaware

Original design application May 31, 1967, Ser. No. 7,309,
now Patent No. 212,023, dated Aug. 20, 1968. Divided
and this application Jan. 30, 1968, Ser. No. 10,361

Term of patent 14 years

Int. Cl. D7—01

U.S. Cl. D36—2

Fig. 1.

Fig. 2.

FIG. 1 is an elevational view of a bowl or similar article showing my new design;

FIG. 2 is a bottom view thereof;

FIG. 3 is a sectional view taken along line 3—3 of FIG. 1;

FIG. 4 is a development of the design; and

FIG. 5 is a sectional view taken along line 5—5 of FIG. 3.

It is understood that the patterns shown fragmentarily in full lines are continued about the entire article in the paths indicated by the broken lines.

The present application is a division of co-pending United States design patent application Ser. No. 7,309 filed May 31, 1967 now design Patent 212,023 of Aug. 20, 1968.

I claim:

The ornamental design for a bowl or similar article, substantially as shown and described.
